CLAIM

The ornamental design for a header card for a container holder, as shown and described.

DESCRIPTION

FIG. 1 is a front view of a header card for a container holder in accordance with the present invention; FIG. 2 is a rear view of the header card for a container holder in FIG. 1;

FIG. 3 is a left side view thereof;

FIG. 4 is a right side view thereof;

FIG. 5 is a top view thereof;

FIG. 6 is a bottom view thereof; and,

FIG. 7 is a front perspective view thereof.

The broken lines shown illustrate portions of the header card for a container holder and form no part of the claimed design.

1 Claim, 7 Drawing Sheets
